UNITED STATES PATENT OFFICE.

WILLIAM FLETT, OF WAKEFIELD, MASSACHUSETTS, ASSIGNOR TO LAWRENCE DUCK COMPANY, OF LAWRENCE, MASSACHUSETTS, A CORPORATION OF MASSACHUSETTS.

SHUTTLE-CHANGING MECHANISM.

Original application filed March 28, 1921, Serial No. 456,314. Divided and this application filed April 18, 1922. Serial No. 555,094.

To all whom it may concern:

Be it known that I, WILLIAM FLETT, a citizen of the United States, residing at Wakefield, in the county of Middlesex and 5 State of Massachusetts, have invented certain new and useful Improvements in Shuttle-Changing Mechanisms, of which the following is a specification.

This invention relates to automatic weft 10 replenishing looms of the type in which two shuttles are used alternately and recharged with new filling during their periods of non-use. A loom of this general character is disclosed in a Barrell Patent 1,207,124 15 granted December 5, 1916, but the present invention consists in certain improvements applicable to looms of the type shown in said patent.

The subject-matter of this invention is 20 disclosed in my copending application Serial No. 456,314 filed March 28, 1921, of which this application is a division pursuant to official requirement.

In looms of the type referred to each 25 shuttle, as filling replenishment is required, is taken away from the change shuttle-box automatically by a carrier that replaces it with the filled shuttle and then transfers the spent shuttle to a charging locality 30 where it is automatically recharged with a filled bobbin. On account of the jarring to which looms are subjected and also on account of the carrying motion of the shuttle-carrier it is necessary to equip the latter 35 with some means for holding the shuttle so securely that it will neither fall from the carrier nor slip out of registration with the recharging means or out of registration with the change shuttle-box as the case may 40 be.

Accordingly an object of this invention is to provide a shuttle-carrier for the purpose mentioned with improved means for holding the shuttles in the desired positions 45 thereon. For reasons that will probably be apparent and that need not be accounted for here the filled shuttle and the spent shuttle occupy different positions on the

shuttle-carrier. This somewhat complicates the problem of providing the shuttle-carrier with adequate means for holding each of the shuttles in the two positions but the present invention provides a solution of this problem. 50

Referring to the accompanying drawings 55 which illustrate a preferred form in which the invention may be embodied,

Fig. 1 represents a top plan view including some of the elements that form the change shuttle-box of a loom and a shuttle-carrier embodying novel features hereinafter described. So far as the change shuttle-box is illustrated it is formed in part by the right-hand end of the lay. 60

Fig. 2 is a view, on a smaller scale, from 65 the right-hand end of a loom looking toward the left and including that part of the lay that helps to form the change shuttle-box. This figure also includes automatic mechanism for ejecting the spent shuttle 70 from the change shuttle-box.

Fig. 3 is a view partly in vertical section and partly in elevation, and on a larger scale than Fig. 1, looking in the opposite direction with reference to Fig. 2 but including none of the elements shown in Fig. 2. The purpose of Fig. 3 is to show a shuttle 75 at the charging locality and also to show the relation between the shuttle-carrier, which is included, and the means by 80 which the shuttle is supported at the charging locality.

Fig. 4 is a view partly in vertical section and partly in elevation of the structure shown in Fig. 1 as viewed from right 85 to left.

Fig. 5 is a perspective view of a shuttle-clamping element with which the shuttle-carrier is provided.

Fig. 6 is a perspective view of another 90 shuttle-clamping element with which the shuttle-carrier is provided.

Since the general organization and operation of looms of this type are more fully described in my aforesaid copending application and also in the aforesaid Barrell 95

patent a relatively brief general statement will suffice for the purpose of this application. The weaving mechanism and the weft replenishing mechanism are organized and controlled so that they operate alternately, each remaining at rest while the other is operating. Assuming that the weaving mechanism is operating and that weft replenishment is required because of a spent 5 or nearly spent condition of the bobbin in the operating shuttle, feeler mechanism of any well-known or preferred construction detects the spent condition of the bobbin and sets in motion automatic means by 10 which the weaving mechanism is stopped and the replenishing mechanism is started. This is controlled in such a way that the weaving mechanism stops in every case when the lay is at or near rear center as 15 shown by Figs. 2 and 4. The power by which the loom is operated is then automatically applied to the replenishing mechanism which includes, as in the well-known Stafford loom, a "change shaft". This 20 shaft is equipped with a disconnectible clutch and carries the several cams or other actuators by which the necessary motions of the replenishing mechanism are imparted. The power being applied to the change shaft 25 by the aforesaid clutch causes the shaft to rotate at a relatively slow speed, for example, one revolution in five seconds. The entire replenishing cycle is effected in one rotation of the change shaft which, during 30 the latter stages of such rotation and after having interchanged the spent shuttle and the filled shuttle, re-applies the power to the weaving mechanism and disconnects it 35 itself from the source of power by incorporating 40 the aforesaid clutch.

To facilitate reference to my aforesaid copending application of which this is a division, the reference characters used therein are used herein to identify the same 45 elements. So far as the change shuttle-box is illustrated it includes a portion of the lay 11 and the usual shuttle-binder 17. An ejector 31 is provided for pushing the spent shuttle toward the front of the loom, 50 or from right to left as in Figs. 2 and 4, or from top to bottom as in Fig. 1. When this occurs the spent shuttle is transferred from the lay to a receiver 32, the spent shuttle being indicated at S', and a filled 55 shuttle being indicated at S. The mechanism for operating the ejector is shown by Fig. 2 and includes an arm 37 the lower end of which is mounted upon a pivot 38 that is carried by and swings forwardly and 60 back with the lay. Operating motion is transmitted to the arm 37 by a rod 35 the lower end of which is pivotally connected to a lever 34. The fulcrum of this lever is indicated at 26. The lever is normally 65 drawn down by a tension spring 42 and is

raised by a cam 33 carried by a shaft 30. This shaft is the one hereinbefore referred to as the "change shaft" which rotates slowly and then only when the weaving mechanism is at rest. Yielding connection 70 between the rod 35 and the arm 37 is afforded by providing the arm with a swiveled block 40 through which the rod extends loosely, and by interposing a helical compression spring 36 between said block and 75 a collar 41 affixed to the rod.

The shuttle-receiver has two separated shuttle-engaging portions 32 connected by a yoke 43, thereby providing a space to receive portions of the shuttle-carrier herein-after described. The normal position of the shuttle-receiver is shown by Fig. 2 and also by broken lines in Fig. 4. After the spent shuttle has been transferred to this receiver as aforesaid the receiver is raised automatically to the position shown by solid lines in Fig. 4. A stem 46 is affixed to the yoke 43 and slides in a bracket 47. The lower end of this stem is connected to mechanism (not shown) by which it is raised to 85 clear the path along which the filled shuttle is carried from the charging locality to the change shuttle-box. A helical compression spring 50 surrounds the stem 46 and its function is to return the shuttle-receiver to 90 its normal position under the control of the operating cam. As shown by Fig. 1 the ends of the shuttle-receiver are provided with flanges 44 which are arranged in grooved guides 45 affixed to the lay. 100

Figs. 1 and 4 show the shuttle-carrier as having moved about half way from the charging locality to the change shuttle-box and as carrying a filled shuttle S to replace the spent shuttle S'. The shuttle-carrier is 105 formed in part by a lever 54 the fulcrum of which is nearly coaxial with the axis about which the lay executes its beating-up movement. The head of the shuttle-carrier is provided with a platform 59 for the spent 110 shuttle and with a pair of fingers 60 which constitute a platform for the filled shuttle. The rear ends of these fingers are turned up as indicated at 61 to stand behind the rear upright surface of the filled shuttle. The front face of the filled shuttle is engaged by a pair of arms 62 formed on the member shown separately by Fig. 5. When the carrier is about to place the filled shuttle on the lay the bottom of the shuttle engages a 115 pair of inclined fingers 63 carried by the lay (see Fig. 4), said fingers being arranged to deflect the shuttle upwardly to the top of the lay and above the upturned ends 61 of the carrying fingers. The latter move 120 into recesses 64 formed in the top of the lay for their reception. 125

Fig. 6 shows a device by which the filled shuttle is clamped against the abutments 62 while it is being transferred from the charg- 130

shuttle-carrier as having started to move from right to left to pick up the filled shuttle and to transfer the latter to the change shuttle-box. The clamping members 62 are 5 about to strike the front face of the shuttle. As the carrier continues to move, the members 62 push the shuttle from the brackets 76, the shuttle-supporting fingers 60 of the carrier meanwhile rising slightly because of 10 the arc through which the carrier swings. These fingers therefore receive the shuttle when the latter is pushed from the stationary brackets 76. While the shuttle is thus being transferred from the brackets to the 15 fingers 60, the finger 212 rides over a roller 213 and is thereby raised so as to increase the distance between the clamping members 62 and 65. The front wall of the shuttle drops between the members 62 and 65 before 20 the trailing end of the finger 212 leaves the roller 213 but subsequently the spring 211 draws down the finger 212 and thereby causes the fingers 65 to clamp the front wall of the shuttle against the members 62. The 25 filled shuttle is thus clamped securely on the carrier until it is deposited in the change shuttle-box where it is released as soon as the finger 75 strikes the yoke 43 as hereinbefore explained.

30 Referring to Fig. 1, the outlying end of filling in the filled shuttle is indicated at *e'* and is attached to a weft-end holder *e* which rests on a tray 184 to which it has been conducted by a chute 182. The filled 35 shuttle has been threaded automatically by the weft-end carrier *e* which has drawn the thread through the throat 87, 88 of the shuttle and into the eye of the shuttle. Fig. 1 also includes a broken line *f'* which represents the stretch of filling running from the 40 fabric to the spent shuttle.

I claim:

1. The combination with a loom, of weft-replenishing mechanism comprising a shuttle-carrier arranged to transfer a filled shuttle to the change shuttle-box, and means on said carrier arranged to clamp the shuttle by the interior and exterior faces of one wall of its bobbin-chamber.

50 2. The combination with a loom, of weft-replenishing mechanism arranged to interchange a filled shuttle and a spent shuttle in the change shuttle-box, said mechanism including a shuttle-carrier by which the filled shuttle and spent shuttle are carried successively, and means on said carrier arranged to clamp one of the shuttles by the interior and exterior faces of one wall of its bobbin-chamber.

60 3. The combination with a loom, of weft-replenishing mechanism arranged to interchange a filled shuttle and a spent shuttle in the change shuttle-box, said mechanism including a shuttle-carrier by which the filled 65 shuttle and spent shuttle are carried suc-

cessively, means on said carrier arranged to clamp one of the shuttles by the interior and exterior faces of one wall of its bobbin-chamber, and means arranged to cooperate with said clamping means to clamp the 70 other shuttle.

4. The combination with a loom, of weft-replenishing mechanism comprising a shuttle-carrier arranged to transfer a filled shuttle to and a spent shuttle from the 75 change shuttle-box, means on the carrier including a movable shuttle-engaging member arranged to clamp one of the shuttles, and means carried by said movable member and arranged to clamp the other said shuttle 80 against said movable member.

5. The combination with a loom, of weft-replenishing mechanism comprising a shuttle-carrier arranged to transfer a filled shuttle to the change shuttle-box, shuttle-clamping means carried by the carrier and including a relatively movable clamping element, and means arranged to move said clamping element so as to release the 85 clamped shuttle in said shuttle-box.

6. The combination with a loom, of weft-replenishing mechanism comprising a shuttle-carrier arranged to transfer a filled shuttle to the change shuttle-box, and spring-stressed means carried by said carrier for clamping the filled shuttle thereon, an element of said clamping means being arranged to strike an element of the change shuttle-box so as to release the filled shuttle 90 in consequence thereof.

7. The combination with a loom, of weft-replenishing mechanism comprising a shuttle-carrier arranged to transfer a filled shuttle to and a spent shuttle from the change shuttle-box, and three shuttle-clamping elements carried by said carrier one of which is arranged to engage the filled shuttle, another of which is arranged to engage the spent shuttle, and the third of which is arranged to cooperate with the first and second alternately to clamp said shuttles in turn.

8. The combination with a loom, of weft-replenishing mechanism arranged to interchange a filled shuttle and a spent shuttle in the change shuttle-box, said mechanism including a shuttle-carrier having cooperative shuttle-clamping jaws one of which is arranged to function against an interior surface of one of the shuttles.

9. The combination with a loom, of weft-replenishing mechanism including a shuttle-carrier arranged to transfer a filled shuttle to the change shuttle-box, said carrier having cooperative shuttle-clamping jaws one of which is arranged to enter the bobbin chamber through the bottom of the shuttle and function against a surface forming said chamber.

10. The combination with a loom, of 130

ing locality to the shuttle-box. This device includes a pair of fingers 65 arranged to extend upwardly into the bobbin cavity of the shuttle and to engage the rear surface 5 of the front wall of the shuttle with a slight pressure, thereby clamping the front wall of the shuttle against the abutments 62. These clamping fingers are affixed to a rock-shaft 66 the ends of which are journaled in 10 bearings 67 in the abutments 62. When these parts are assembled the fingers 65 project from the abutments through openings 68. The clamping device for the filled shuttle is thus supported entirely by the 15 abutments 62 although the latter are movable relatively to the head of the carrier. As shown by Figs. 4 and 5 the abutments 62 are parts of a member comprising an arm 69 and having a hub mounted upon 20 a rod 70. This rod is fixed to the carrier, and the element including the abutments is arranged to turn relatively thereto so as to clamp and release the spent shuttle. A torsion spring 71 encircling the rod 70 eng- 25 gages the arm 69 and is anchored to a collar 72. The spring normally raises the abutments to the position shown in Figs. 3 and 4 in which position the space between the abutments 62 and those indicated at 73 is 30 slightly less than the width of the shuttle. This construction enables the abutments 62 and 73 to clamp the spent shuttle resting on the platform 59.

When the carrier has moved toward the 35 lay far enough to place the filled shuttle on the lay the abutments 62 are depressed sufficiently to increase the space between them and the abutments 73 to slightly more than the width of a shuttle; and while they 40 are so spaced the spent shuttle is deposited on the platform 59 by the shuttle-receiver 32. The aforesaid separation of the abutments 62 from the abutments 73 is produced by a finger 74 rigidly related to the abutments 62 and arranged to strike the yoke 43 before the shuttle-carrier reaches the limit of its movement toward the lay. When the 45 carrier subsequently moves away from the lay toward the charging position the abutments 62 are raised by the springs 71 and are thereby caused to clamp the spent shuttle against the abutments 73. The clamping fingers 65 are operated in like manner by a finger 75 which also strikes against 50 the yoke 43. The clamping action of these fingers is produced by a tension spring 211 one end of which is anchored to the arm 54 and the other end connected to a finger 212 rigidly connected to the clamping fin- 55 gers as shown best by Fig. 6. In this case the fingers 65 are moved to release the filled shuttle as the latter slides on the lay toward the shuttle-binder 17, the filled shuttle being thus completely released from the 60 carrier before the latter is arrested and 65

thereafter sliding on the lay so as to pass over and beyond the fingers 65 until it is arrested by the binder.

The shuttle carrier, having received the spent shuttle from the receiver 32, swings 70 toward the front of the loom with the spent shuttle clamped thereon and passes between two fixed shuttle supporting brackets one of which is shown in Fig. 3 and indicated at 76. Referring to Fig. 3 the shuttle-carrier moves from left to right to transfer the spent shuttle to the charging locality, and from right to left to transfer the filled shuttle from the charging locality to the change shuttle-box. When moving from 80 left to right with the spent shuttle between the clamping members 62 and 73 the shuttle is arrested by a fixture 77 while the carrier is in motion, the carrier thereafter continuing to move toward the right so that 85 the clamping members 62 yield against the stress of the spring 71 and pass under and beyond the shuttle. The supporting brackets and the fixture 77 are integral and, as shown in my aforesaid copending application, are arranged at one end and are affixed to the breast beam. When the carrier is at the right-hand limit of its movement the fingers 60 are at the right of the shuttle to clear a space directly under the 90 shuttle so that the spent bobbin may drop without encountering any obstacle.

Fig. 3 also includes two filled bobbins D and E, the latter having been depressed into the shuttle from the position occupied by 100 the bobbin D and having been replaced by the bobbin D which will subsequently be depressed into the other shuttle. The bobbin D is supported in part by yielding fingers 110 pivoted at 111 and normally held 105 in the position shown by a tension spring 112. Each bobbin, on reaching the position occupied by the bobbin D, is registered lengthwise of the shuttle by a tappet 188. This tappet is fixed to a rockshaft 189 110 journaled in a bearing 191 and having a finger 192 arranged to be engaged and displaced by a portion of the shuttle carrier. The tappet 188 is arranged to engage the tip end of the bobbin. The bobbins and 115 shuttles are well-known products of the Draper Company and need not be described excepting to state that the shuttles are equipped with spring clamping jaws in the bobbin cavities and the larger ends of the 120 bobbins are provided with metallic rings which are forced between the jaws as the bobbins are depressed by a hammer (not shown).

As shown by Fig. 3 the finger 212 rests 125 on a shoulder 158 of the shuttle-carrier. Under this condition the space between the clamping members 62 and 65 is less than the thickness of the front wall of the bobbin cavity of the shuttle. Fig. 3 represents the 130

means for supporting a filled shuttle outside the change shuttle-box, and shuttle-changing mechanism including a carrier arranged to transfer said shuttle from said supporting means to said shuttle-box, cooperative shuttle-clamping jaws one of which is

the other, and means arranged to retract said spring-stressed jaw for the reception of the shuttle.

In testimony whereof I have affixed my signature this 27th day of October 1921.

10

WILLIAM FLETT.
